UNITED STATES PATENT OFFICE.

ALBERT SCHMID, OF PITTSBURG, PENNSYLVANIA.

ARMATURE FOR ELECTRIC MACHINES.

SPECIFICATION forming part of Letters Patent No. 505,926, dated October 3, 1893.

Application filed November 3, 1892. Serial No. 450,881. (No model.)

To all whom it may concern:

Be it known that I, ALBERT SCHMID, a citizen of the United States, residing in Pittsburgh, in the county of Allegheny and State of Pennsylvania, have invented a new and useful Improvement in Armatures for Electric Machines, (Case No. 493,) of which the following is a specification.

The invention relates to the construction of armatures or field-magnets of electric generators and motors, the object being to simplify and improve the construction.

The improvements are especially useful in machines of large size.

15 The invention consists principally in the novel form and method of constructing and supporting the poles or pole-pieces of the machine.

It has been customary heretofore to construct armatures from plates or sheets of metal stamped in shape to correspond with the cross-section of the armature, a sufficient number of these plates being laid together to build up the entire armature core. In the 25 case of large machines especially this is a difficult and expensive plan of construction.

My invention consists in constructing the main portion or body of the armature or the field-magnet in the form of a ring or wheel of 30 proper dimensions, suitable recesses being provided for receiving the pole-pieces of the armature. The pole-pieces themselves and the principal magnetic portions are formed of sheet metal stamped to the proper size and 35 shape, and built up and mounted in the openings in the ring designed to receive them. The shapes of these pole-pieces and the details of construction will be described more particularly in connection with the accompanying drawings.

In the drawings Figure 1 is a side elevation of a portion of an armature and corresponding portion of the field-magnet of a machine, the improvements being shown in the section 45 of the armature. Fig. 2 is a cross-section along the line x, x , Fig. 1.

Referring to the figures, A represents a portion of the body of the armature core which is constructed in a ring form and is supported 50 by spokes. This ring portion is formed with openings preferably T-shaped as shown at B. The principal magnetic portion of the arma-

ture is built up of laminæ of soft iron and is supported by the ring A. The plates or laminæ are secured together by bolts d, or in any other suitable manner. In large machines, especially it is desirable to form the magnetic portion C in sections a as shown in Fig. 1. Each section may contain one entire pole c' and a half of each of the adjacent poles c², c³. 60 These sections c are formed with arms e having lugs e' which enter corresponding lateral openings B in the ring. When the sections are placed in the ring A, the ends of the adjacent sections fit against each other along 65 the lines f, making a complete series of poles about the armature ring. A suitable filling material, such as Babbitt metal or molten lead is then poured in around the portions entering the armature ring as shown at g, thus 70 securely fastening the entire pole structure into the ring. It will be seen that the magnetic circuit from pole to pole is complete through the structure of the pole sections independently of the supporting ring A, each section 75 being approximately H-shaped with the addition of an intermediate projection on one side forming a tooth or pole. The central portion of each section may stand clear from the body of the ring A leaving an open space between the 80 two, through which air is free to circulate, thus cooling the insulation.

The shapes of the pole-pieces or teeth may be variously modified as found convenient and desirable in different cases. The form 85 shown in the drawings is provided with lateral projections c³ beneath which the armature coils K are placed. These coils may be wound in position, or they may be previously wound and insulated and then placed over 90 the ends of the pole-pieces and pressed into position beneath the projection c³. The field-magnet to which this armature is applied may be of any suitable construction. In the drawings I have shown a field-magnet ring M, having poles m, projecting therefrom and supplied with coils m' secured thereto in any convenient manner.

It will be understood that although I have described the invention more particularly in 100 connection with the armature, oftentimes it may be desired to construct the revolving portion of the machine as a field-magnet, and the invention will be of course applicable

thereto, and likewise certain features of the invention are applicable to the stationary portion of an electric machine whether field-magnet or armature.

5 I claim as my invention—

1. In an electric machine the combination of a supporting ring having transverse openings, polar projections consisting of plates secured therein, each plate containing one complete coil receiving tooth and fractions of two other similar teeth, substantially as described.

10 2. In an armature for an electric machine, radiating polar projections formed of sheet metal stamped to the proper size and shape and fastened together face to face, a support therefor consisting of a ring having trans-
15 verse openings, and a shaft carrying the ring, substantially as described.

3. The combination with the supporting 20 ring A, having the openings B, of the polar teeth C built up as described, and having the

arms e entering said openings, substantially as described.

4. In an armature or field-magnet for electric machines a series of laminated pole-pieces, 25 a support therefor having openings beneath the alternate poles and arms extending from the pole-pieces into said openings respectively.

5. In an armature for electric machines, an 30 annular magnetic ring carrying pole-pieces and an inner supporting ring carrying the same independently of which the magnetic circuit is completed.

In testimony whereof I have hereunto sub- 35 scribed my name this 1st day of November, A. D. 1892.

ALBERT SCHMID.
